(57) **CLAIM**

The ornamental design for a shroud for weight stack, as shown.

DESCRIPTION

FIG. 1 is a front perspective view of a shroud for weight stack in an environment.

FIG. 2 is a front perspective view of the shroud for weight stack of FIG. 1.

FIG. 3 is a rear perspective view of the shroud for weight stack of FIG. 1.

FIG. 4 is a front view of the shroud for weight stack of FIG. 1.

FIG. 5 is a rear view of the shroud for weight stack of FIG. 1.

FIG. 6 is a right side view of the shroud for weight stack of FIG. 1.

FIG. 7 is a left side view of the shroud for weight stack of FIG. 1.

FIG. 8 is a top view of the shroud for weight stack of FIG. 1; and,

FIG. 9 is a bottom view of the shroud for weight stack of FIG. 1.

In the figures, the dashed lines indicate environmental features that form no part of the claimed invention.
